METALLURGICAL FURNACE

Paul B. Tonnar, Cleveland, Ohio

Continuation of application Serial No. 611,022,
 May 13, 1932. This application August 17, 1932,
 Serial No. 629,249

7 Claims. (Cl. 263—15)

This invention relates to metallurgical furnaces and more particularly to improved open hearth furnace construction and to improved methods and apparatus for firing such furnaces.

5 In the present types of open hearth furnaces the fuel, if of a nature not requiring preheating, and the air for its combustion, are introduced through suitable ports in one end of the furnace and the products of combustion are caused to pass out of the other end of the furnace through similar ports and then through suitable checkerwork in which a large part of their contained heat is stored.

At intervals of about fifteen minutes, this operation is reversed and the air is caused to pass first through the checker-chamber previously mentioned in which it is preheated and then through the ports where it joins with the fuel, then into the furnace and the products of combustion then pass out of the furnace through the ports by which the air entered during the previous cycle, and then through the checkerwork at that end of the furnace to heat it so that it may preheat the air when the furnace is again reversed.

In cases where the fuel used is producer gas or other low heat value gas, or under circumstances where it is desirable, the checker chambers are so divided that the fuel gas may enter the furnace through one part and be preheated while the air for its combustion is passing through and being preheated by the other part of the checkers.

In these cases the outgoing hot gases pass, part through one section of the checkers and the balance through the other section, so that both sections shall be hot and prepared to preheat both the gas and air when the furnace is reversed.

In other cases, where high heat value fuels are used, these fuels, whether solid, liquid or gaseous, are not preheated but are introduced into the current of preheated air as it enters the end of the furnace, in such a manner as to produce the most advantageous combustion possible under the circumstances.

45 From this description of the standard open hearth furnace of the present time, it will be readily understood that all definite control of the direction of the flame is impossible as the entering ports for the air and fuel are subjected to the intense heat of the outgoing gases when the furnace is reversed, and as all of the fuel must enter through one port, its intimate mixture with the air is impossible and the flame is accordingly long and often extends or persists to the further end

of the furnace and even into the outgoing flues and checkers.

As a modern open hearth furnace is usually more than sixty feet in length, and as the flame always passes in only one direction at a time, its impingement on a solid charge to be melted is from one direction only.

In conventional practice, during the early stages of the heat, scrap or other solid components of the charge are piled high on the furnace hearth. During these early stages it is desirable to fire as hard as may be possible to more quickly reduce the solid materials to the molten state in order to minimize the loss of metal by oxidation. A fuel such as oil, tar or coke oven gas entering 15 the furnace from a single port or burner, at considerable velocity, is deflected from the surfaces of the solid materials toward the roof upon which it may impinge with very detrimental effect. This action is due to the relatively short distance between the fuel port and the piled charge, to the large volume and high velocity of the flame of burning gases, and to the fact that mixing of the fuel with the air is relatively slow, so that combustion is still taking place when the flame impinges on the roof with destructive effect. 20

Frequently the rate of firing may be severely limited by the ability of the roof to withstand the temperature and erosive effects of high rate firing without failure.

30 The invention herein described contemplates an open hearth furnace wherein any combustible mixture which hereafter will be deemed as a suitable fuel in the presence of air adequate for substantially complete combustion, may be used. 35 For example, oil, tar or coke oven gas is projected into the furnace through the medium of an adjustable firing port from a fuel tube disposed within the nose piece of the firing port, and is burned with preheated air introduced with or about it. This mixture is delivered to the furnace chamber through a plurality of firing ports in a plurality of directions.

The firing ports are so designed that they may be easily swiveled, either horizontally or vertically, to the end that the flame from each may be accurately directed against that part of the charge where it will do its work most effectively and may be redirected from time to time toward other points so that during the entire period of making a heat the flame from each firing port may perform its function to the best advantage. When making up the bottom, between heats, the firing ports may also be so moved as to direct the flame from each against 50 55

that part of the bottom requiring the most intense temperature.

During the melting of the charge, but more particularly after the stock is all melted, the several firing ports may all be directed so that the flame from each may be tangent to an imaginary circle more or less concentric with the furnace, or so as to produce a turbulent or cyclonic action of the combustible mixture and its products with a resultant rapid and complete combustion and a more intimate contact of the gases with the bath and a more complete absorption of the heat by the furnace charge. It is desirable to maintain a localized zone of combustion directly above the central part of the charge and in intimate contact therewith as long as is possible, so that all of the combustible mixture will be burned and only waste gases will be taken from the furnace.

In the invention herein being described, the combustible mixtures enter at four points rather than at the single point of conventional practice, and enter through each firing port in only one-fourth the volume. The effect of the decrease of mass will operate to decrease the linear distance required for the admixture of air and fuel and its complete combustion, to a marked degree, and accordingly when using my invention the furnace may be fired to its maximum toward the surface of the solid materials without the liability of the combustible mixtures reaching the roof in an unburned state.

In open hearth furnace operation physical and chemical limitation of combustion are such that the differential of temperature between the flame and the bath is relatively small. Owing to the more intimate and rapid mixing and the consequent more rapid combustion, a greater heat release is accomplished in a given furnace volume. This obviously has the effect of increasing the temperature of the flame, thus increasing the differential of temperature above mentioned, causing the operation of refining the steel to be accomplished in much less time and more efficiently than is usual by the older methods.

This application constitutes a continuation of my application, Serial No. 611,022, filed May 13, 1932.

Other advantageous features will appear in the following detailed description which, considered in conjunction with the accompanying drawings, sets forth the preferred embodiment of my invention, wherein:

Figure 1 is a plan view partly in section of an open hearth furnace including the regenerator chambers therefor employing my invention;

Figure 2 is a front elevation partly in section taken along the line 2-2 of Figure 1;

Figure 3 is a side elevational sectional view taken along the line 3-3 of Figure 1;

Figure 4 is a top plan view partly in section illustrating a modified form of my invention wherein a suitable recuperator is provided to preheat air for continuous operation;

Figure 5 is a modified form of my invention wherein suitable regenerators are provided to preheat both air and gas;

Figure 6 is a sectional view taken on the line 6-6 of Figure 5;

Figure 7 is a sectional view taken on the line 7-7 of Figure 5;

Figure 8 is a sectional view illustrating a modified adjustable firing port adapted to be used with my modified furnace structure.

With reference to the accompanying drawings

and particularly Figures 1 to 3 inclusive, there is illustrated the preferred embodiment of my invention comprising an open hearth furnace designated in its entirety by the numeral 1 and including the regenerators 2 and 3. The open hearth furnace 1 is of the usual construction and includes a front wall 4, back wall 5 and bulkheads 6 and 7, which define a refining chamber 8 having a hearth 9 disposed therein. The bulkheads 6 and 7 which are situated at opposing ends of the refining chamber 8 are identical in construction and comprise a single downtake flue 10 having firing ports 14 with fuel tubes 11 associated therewith disposed on each side thereof. The term "firing port" hereinafter used is deemed to designate the entire adjustable unit through which the fuel and air are projected into the furnace chamber. The downtake flues 10 are adapted to connect the chamber 8 with the slag pockets 12 and convey the products of combustion from the refining chamber to the regenerators 2 and 3.

The provision of but a single flue in the bulkheads of the furnace through which the products of combustion are conveyed from the laboratory or chamber 8 permits the hearth to be built up at the ends. These built up ends will not allow the charge to boil over into the downtake flue and slag pockets. Furthermore, it is not material to the operation of this furnace whether or not the walls of this flue become eroded as the velocity, direction and control of the flame is not dependent on its size or construction as the firing ports through which the combustible mixtures are introduced into the chamber are entirely independent in their operation from the discharge ports.

The bulkheads 6 and 7 are connected with the front and back walls of the chamber by suitable walls 13. Disposed adjacent the exterior of each of the walls 13 is a firing port 14, the nose of which projects therethrough and communicates with the interior of the furnace. Each of the firing ports 14 has associated therewith a fuel tube or burner 11. The firing ports are adjustable and may be so directed and redirected as to cause a flame projected thereby to melt the stock to the best advantages at all times during the melting period of operation and may later be again redirected so as to produce a "tangential" system of firing over the charged material. This system produces violent cyclonic action and turbulence of the combustible mixtures directly over a portion of the charged material and assures rapid and complete combustion thereof within the furnace chamber. Each firing port may be adjusted to project the combustible mixture independent of the other firing ports and co-operation between firing ports may be such as to divert the flames from their original projected direction.

The firing ports 14 are so adjustable that they may be disposed at any angle with relation to the bottom of the furnace. On sintering the furnace bottom, it may only be necessary to use the flames from one or two firing ports, and these can be made to sweep the entire surface of the hearth. The provision of firing ports as disclosed in my invention provides a continuous firing of the furnace at all times during its operation. Furthermore, the direction and intensity of the flame can be controlled at all times. A plurality of short flames disposed so as to create a turbulence or change in direction of the com-

combustible mixture is effective in obtaining a more complete combustion.

Adjacent the end of each of the downtake flues 10 of the respective bulkheads 6 and 7 a slideable valve 15 and 16 respectively is disposed to preclude the flow of products of combustion from the chamber 8 during certain periods of the operation of the furnace. The valves 15 and 16 are slidably mounted in water cooled guide members 17 and 18 respectively, secured in the walls of each of the flues 10.

The exhaust flues 10 terminate at their lower ends in slag pockets or pits 12. Each of the regenerator units 2 and 3 is identical in design, and is of the usual construction, the chamber of which is provided with checker brick which absorb a portion of the heat from the waste gases which pass alternately therethrough from the furnace, and give up heat to the cold air passing through the previously heated chamber to the firing ports 14, communicating with the interior of the open hearth chamber 8.

The waste gases are exhausted from the regenerator chamber through ports 23 and conveyed to either a waste heat boiler or stack (not shown) through flue 36 as desired. In conveying the air to the firing port and in turn directing the same into the furnace chamber the hereinabove procedure is reversed, the cool air is introduced into the regenerator chambers through either the valve 20 or 21 and in passing therethrough is heated. The heated air is conveyed from the uppermost part of the regenerator through flues 24, 25, 26, 27, 28, and 29 to the firing port 14 where the air and fuel mixture is ejected into the laboratory chamber 8 of the furnace in such volumes and at such velocities as are commensurate with the most efficient operation of the open hearth furnace.

Adjacent the end of each of the flues 25 is provided a water cooled slideable valve 30 or 31 respectively which valves are vertically actuated by any suitable means in guide members 32 disposed in the side walls of the flue.

The firing ports 14 and related structure as depicted in Figures 1 and 3 are disclosed in detail and claimed in my co-pending application, Serial No. 627,922 filed August 8, 1932.

These firing ports 14 are adjustably mounted exteriorly of the furnace walls, on pedestals 33 forming the upper ends of the vertical flues 29. The firing ports are preferably formed of sheet metal with refractory lining and adjustably carried in brackets 34 mounted on a turntable 35 suitably sealed against air leak, the same projecting into or through the walls 13 of the furnace proper, suitably sealed clearance being provided in the walls about the ends of the nose portion of the firing ports to permit considerable amount of vertical and lateral adjustment, thus making it possible to direct the combustible mixture from the firing port as desired. The fuel tubes 11 mounted in the adjustable firing ports 14 and movable therewith assure the ever present and close proximity of the air supply to the fuel emitting from the firing port, resulting in a more ready and perfect combustion thereof.

In the operation of the open hearth furnace herein disclosed which embodies my invention, the valve 15 in the downtake flue 10 of the bulkhead 6, valve 31 in the preheated air flue 25 and stack valve 38 are closed. Cold air is adapted to be introduced into the regenerator unit 2 through valve 20 and ports 23 and in passing therethrough is heated. The heated air is con-

veyed from the regenerator 2 to the firing port 14 through flues 24, 25, 26, 27, and 28 and upwardly through the vertical flues 29. The preheated air along with the fuel referred to as combustible mixture is directed into the furnace through the four firing ports at an angle so that a vortex is formed directly above the charge by the burning gases producing violent cyclonic action and turbulence, or the firing ports may be directed to project the flame in any other direction which will effect the most economical operation of the furnace. Adjacent streams of combustible mixtures projected in the same general direction across the furnace may be converged, or streams of combustible mixtures from opposite direction may impinge upon each other whereby the streams of combustible mixtures are diverted from the original projected direction. The burned gases are conveyed from the furnace chamber through valve 16 and the downtake flue 10 of bulkheads 7, slag pocket 12, through the regenerator unit 3, and thence conducted through the ports 23, valve 39 and flue 37 to any suitable means of disposal, either to a stack or waste heat boiler (not shown) as the case may be. At such time as the checkerwork of the regenerator unit 2 has released the greater part of its absorbed heat, valves 16, 30, and 38 are closed and valves 15, 31, and 39 are opened and cold air is admitted through valve 21 and inlet ports 23 to the regenerator unit 3 where it is heated and conveyed therefrom to the firing ports 14 through suitable conduits or flues as hereinabove referred to.

Referring now to Figure 4 there is illustrated a modified form of my invention comprising an open hearth furnace 39 including a chamber 40 having exhaust ports or downtakes 41 disposed at opposite ends of the chamber. Associated with the downtake flues are suitable slag pockets 42 and flues 43 which are adapted to convey the products of combustion from the downtake to a suitable recuperator 44. The products of combustion pass from the recuperator through flue 45 to a stack or waste heat boiler (not shown). Air is introduced into the recuperator by a blower 46 and in passing therethrough is heated. The heated air is then conveyed from the recuperator to the firing ports 47 through flues 48, 49, and 50, 50.

In the operation of the modified form of my invention wherein a recuperator is provided in the place of regenerator chambers, the products of combustion pass continuously from the chambers 40 through downtakes 41 disposed at each end thereof, and heated air continuously passes from the recuperator 44 to the firing port 47.

With reference to Figures 5 to 8 inclusive there is illustrated an open hearth furnace organization which may be of the same construction as shown in Figure 1 except that it is adapted to operate with producer gas or the like which is preferably preheated before being introduced into the furnace and used as fuel. The regenerators 2 and 3 are preferably formed with two longitudinal chambers 51a and 52, the former to preheat the air and the latter to heat the gas. The gas to be preheated is introduced from gas supply duct 51 into a flue 53, which conveys the same to the regenerator chamber 52. The gas is heated while passing therethrough and is conveyed therefrom to the firing port 14 through flues 54, 55, 56, and 57 and the inner flue 58 of concentric vertically disposed flues. The air to be heated is introduced into a conduit 75

59 through a valve 60 and is conducted to the chamber 51 of the regenerator wherein it is heated and conveyed to the firing port 14 through flues 61, 62, 63, 64 and through vertical flue 65. Valves 66 are provided in the flue leading from the slag pockets 12 to the regenerators and are closed when gas and air are heated in the regenerators 51a and 52 and are opened when hot furnace gases are permitted to pass therethrough to heat the checkerwork disposed therein. Similarly the valves 67 and 68 are open or closed to direct the hot burned gases from the regenerators to the stack or waste heat boiler. Valves 69 and 70 are disposed in the flues 54 and 61 respectively and are closed when the valves 66 are opened to direct the hot gases from the furnace chamber through the regenerator and prevent the escape thereof into the flues leading to the firing ports.

20 It will be seen that I have provided a furnace wherein there is a continuous non-reversing firing during the heating and treating of a charge and wherein the numerous disadvantages of present open hearth practice as hereinabove set forth have been minimized and in many instances entirely eliminated.

Although the foregoing description is necessarily of a detailed character in order to completely set forth this invention, it is to be understood that the specific terminology is not intended to be restrictive or confining and it is further understood that various re-arrangements of parts and modifications of structural detail may be resorted to without departing from the scope or spirit of the invention as herein claimed.

I claim:

1. An open hearth furnace having a refining chamber, outlet ports disposed at opposite ends of the furnace for continuously conveying waste gases from the chamber, inlet ports for discharging streams of air into the chamber disposed in pairs on opposite sides of each outlet port, means for projecting fuel into the chamber within each of said air streams and means for adjustably controlling the angle of projection of the air stream into the chamber.

2. An open hearth furnace having a refining chamber, outlet ports disposed at opposite ends of the furnace for continuously conveying waste gases from the furnace, an inlet port disposed on each side of each outlet port for discharging combustible mixtures into the chamber simultaneously with the discharge of waste gases from the chamber through the outlet ports, and means for varying the angle of projection of the combustible mixtures into the furnace.

3. An open hearth furnace having a refining chamber of generally rectangular formation, down-take exhaust flues located at opposite ends

of the chamber and serving only as passages for continuously conveying waste gases from the chamber, and inlet ports for continuously discharging combustible mixtures into the chamber simultaneously with the escape of waste gases through said exhaust flues, said inlet ports being disposed on opposite sides of each exhaust flue and arranged to continuously discharge the said mixtures from opposite ends of the furnace at converging angles toward the central portion of the chamber.

4. An open hearth furnace having a refining chamber of generally rectangular formation, down-take exhaust flues located at opposite ends of the chamber and serving only as passages for the escape of waste gases from the chamber, and movably mounted inlet ports for discharging combustible mixtures into the chamber simultaneously with the escape of waste gases from the chamber, said inlet ports being disposed on opposite sides of each exhaust flue.

5. An open hearth furnace having a refining chamber of generally rectangular formation, down-take exhaust flues one at each end of the chamber and serving only as passages for the escape of waste gases from the chamber, and firing ports located at opposite ends of the furnace on each side of the respective exhaust flues and having a nose portion projecting thru the wall of the furnace, said ports being adjustable to vary the angle of projection of the nose portion.

6. An open hearth furnace having a refining chamber of generally rectangular formation, down-take exhaust flues located at opposite ends of the chamber and serving only as passages for continuously conveying gases from the chamber and firing ports for continuously introducing fuel into the chamber simultaneously with the escape of waste gases through said exhaust ports, said firing ports being disposed on opposite sides of each exhaust flue and adjustable to continuously introduce fuel from opposite ends of the furnace at converging angles towards the central portion of the chamber.

7. An open hearth furnace having a refining chamber of generally rectangular formation, down-take exhaust flues located at opposite ends of the chamber and serving only as passages for continuously conveying gases from the chamber and adjustable means for continuously introducing fuel into the chamber simultaneously with the escape of waste gases through said exhaust ports, said means being disposed on opposite sides of each exhaust flue and arranged to continuously introduce fuel from opposite ends of the furnace at converging angles toward the central portion of the furnace.
